United States Patent Office

Des. 214,601
Patented July 1, 1969

214,601

STAPLER

William L. Gaya, Summit, N.J., assignor to The Bates Manufacturing Company, Orange, N.J., a corporation of New Jersey

Filed Oct. 30, 1968, Ser. No. 14,234

Term of patent 14 years

Int. Cl. D19—02

U.S. Cl. D74—1

FIGURE 1 is a full-size side elevation of a stapler, showing my new design, the other side elevation being the mirror image thereof;

FIGURE 2 is an elevational view of the front end of the stapler;

FIGURE 3 is a similar view of the rear end of the stapler;

FIGURE 4 is a top plan view thereof;

FIGURE 5 is a horizontal sectional view taken on the plane of the line 5—5 of FIGURE 1.

I claim:

The ornamental design for a stapler, as shown and described.
